UNITED STATES PATENT OFFICE.

JACOB FAUST, OF PASSAIC, NEW JERSEY.

STEAM PRESSING IRON.

Application filed September 24, 1926. Serial No. 137,546.

This invention relates to improvements in sadirons and has particular reference to a steam pressing iron for tailors and the like.

The primary object of the invention resides in the provision of a means for utilizing the heat from a heating element contained within the body of the iron and used for heating the same for generating steam which is led from a steam chamber to the ironing face of the iron adjacent the toe thereof, whereby the goods to be pressed are moistened during the pressing operation, thus eliminating the moistening of the goods usually required before ironing.

Another object of the invention is to provide a steam pressing iron which includes a means for preheating water leading to a boiler actuated upon by the heat of the heating element contained in the iron where by water entering the boiler is turned into steam for escape through ducts which lead to the face of the iron.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a vertical longitudinal sectional view through my improved pressing iron.

Figure 2 is a vertical transverse sectional view on the line 2—2 of Figure 1.

Figure 3 is a horizontal sectional view on the line 3—3 of Figure 1.

Referring more particularly to the drawing, the reference numeral 10 designates my improved pressing iron in its entirety which includes a hollow body 11 having a flat base or pressing surface 12, and which body houses a heating element in the nature of a gas burner 13, which in the present form of iron serves to heat the base 12 for ironing purposes. A flexible tube or hose 14 leads from the burner 13 to a source of gas supply. The body 11 has a handle 15 secured thereto by which the iron is held by the operator during its movements over the goods to be pressed.

The toe end of the base 12 has a boss 16 rising from the inner face thereof, the exterior of the boss being screw threaded for connection with the threaded end of a cylinder 17 which constitutes a steam generating chamber, which is positioned for-

ward and adjacent the burner 13 to be heated by the flame therefrom. The upper end of the cylinder extends above the top of the body of the iron and is internally screw threaded for threading engagement with a closure cap or plug 18 which may be removed for access to the steam generating chamber when desired to clean the inside of said chamber. A pipe 19 enters the cylinder and depends to a point adjacent the bottom thereof and which pipe leads from a pipe coil 20 disposed beneath the burner 13. The outlet end of the pipe 19 is normally sealed by the water within the steam generating chamber to prevent steam from backing up therein when the flow of water to the chamber is shut off. A water supply hose 21 has one of its ends connected with the pipe coil 20 and which hose is provided with a suitable control valve 22 for regulating the flow of water through the pipe coil 20 to the cylinder.

The boss 16 is provided with steam outlet ducts 23 which open into the cylinder at one end and onto the ironing face of the base 12 whereby communication is established between the interior of the cylinder and the face of the iron. The interior of the cylinder may be termed a chamber and will be referred to as such hereinafter. The steam ducts 23 enter the chamber adjacent the top thereof by providing tubes 24 which rise from the boss.

In practice, the burner is lighted in the usual manner and permitted to heat up the iron after which the valve 22 is turned on to permit a limited amount of water to flow into the pipe coil 20 where it is preheated before entering the chamber where it is accumulated. The water being preheated before entering the chamber, the same will immediately turn into steam due to the action of the intense heat from the flame, which flame heats the walls of the chamber. As the steam pressure in the chamber increases, the steam will find its way out of the ducts 23 and will penetrate the goods being pressed whereby to moisten the same prior to the passage of the major portion of the iron thereon.

While I have described what I deem to be the most desirable embodiment of my invention, it is obvious that many of the details of construction may be varied without in any way departing from the spirit of my invention, and I therefore do not limit my

self to the exact details of construction herein set forth nor to anything less than the whole of my invention limited only by the appended claims.

5 What is claimed as new is:—

1. A pressing iron comprising a hollow body having a heating element arranged therein, a cylindrical steam generating chamber arranged in juxtaposition to said heating element, the walls of said steam generating chamber being subjected to the heat from said heating element, steam outlet ducts leading from the pressing face of the iron to the interior of said steam generating chamber and opening into the same adjacent the top thereof, a water pipe extending downward into said steam generating chamber and terminating short of the bottom thereof, a pipe coil connected with said water pipe and disposed adjacent said heating element, a hose leading from said

- 20

pipe coil to a suitable water supply, and means for controlling the flow of water from said water pipe, substantially as and for the purpose specified. 25

2. A pressing iron comprising a hollow body having a heating element arranged therein, a cylindrical steam generating chamber arranged in juxtaposition to said heating element, the walls of said chamber being subjected to the heat of said heating element, steam outlet ducts leading from the pressing face of the iron to the interior of said steam generating chamber, a water pipe extending into said steam generating chamber, and a pipe coil connected with said water pipe and disposed adjacent said heating element substantially as and for the purpose specified. 30

35 In testimony whereof I have affixed my signature.

JACOB FAUST.
